UNITED STATES PATENT OFFICE.

ALEXANDER S. SPEER, OF BUFFALO, NEW YORK, ASSIGNOR, BY MESNE ASSIGNMENTS,
TO THE BEAVER PRODUCTS COMPANY, INC., A CORPORATION OF NEW YORK.

BRANDING ROOFING.

Application filed December 28, 1920, Serial No. 433,624. Renewed October 9, 1922. Serial No. 593,462.

To all whom it may concern:

Be it known that I, ALEXANDER S. SPEER, a citizen of the United States, residing at Buffalo, in the county of Erie, State of New York, have invented certain new and useful Improvements in Branding Roofing; and I do hereby declare the following to be a full, clear, and exact description of the invention, such as will enable others skilled in the art to which it appertains to make and use the same.

This invention relates to improvements in apparatus for branding composite sheet building material, such as composite roofing.

Among other objects the invention is intended to provide novel and improved apparatus for placing designs or identifying data on such materials without marring or disturbing the face side thereof, but which designs or data are nevertheless clear and distinct and cannot be readily obliterated.

The nature of the invention may be best understood by reference to one illustrative construction embodying the invention and shown in the accompanying drawing.

In the drawing

Figure 1 is a side view of the improved machine,

Figure 2 is a plan view of the printing or die roll,

Figure 3 is an enlarged detailed section of the roll,

Figure 4 is an end view showing a modified arrangement.

I have illustrated the invention in connection with a machine for cutting asphalt roofing into units such, for example, as the machine of my Patent No. 1,244,654, granted October 30, 1917, although, as will be obvious, the invention is capable of use independently of any other machine for handling or treating the material. Moreover, it is contemplated to employ the invention in connection with material which is formed into rolls and not cut into units.

Preferably the material is impressed with the designs, data or trademarks as one step in the continuous process of manufacture of the units of the material. This saves cost in handling and is otherwise a convenient mode of employing the invention. In the case of asphalt roofing, this material is still warm and somewhat soft and sticky when the designs are impressed therein. When the material is cut into a number of units,

such as individual shingles or strips, it is desirable that each unit bear the trademark or whatever impression it is desired to place on the material.

To embody the invention in the machine of the patent above referred to I substitute for the feed or pulling rolls of the machine forming the subject-matter of the above patent a printing or die roll 1 and a platen roll 2, and I contemplate arranging the printing roll either below the web as shown in Figure 1 or above the web as shown in Figure 4 for a reason to be presently set forth. The said machine comprises a frame 3 in which are journaled the rolls 1 and 2 in a manner to be presently described and this frame carries also cutting rolls 4 and 5, which engage opposite sides of the web to cut the same in the manner set forth in the above mentioned patent. Between the cutting rolls and the printing and platen rolls the web passes over a table as shown, and the roll 2 is spring pressed toward the roll 1, the web passing between the said rolls. This arrangement permits the platen roll to conform itself to varying thicknesses of the web.

The printing roll 1 or equivalent member is provided on its peripheral surface with a series of depressions 6, and within each of these depressions there is arranged a die 7. The dies are so spaced on the die-roll that as the web passes between the rolls 1 and 2 the impression will be properly placed on the web, to correspond with the arrangement of the shingles in the web. Each of these dies, which bear any desired figure or label is held within the recesses 6 in any suitable or desired manner. The mounting of the dies on the printing member is such that the bodies thereof lie below the surface of the printing member and only a portion of the sharp cutting edges project above the surface. Accordingly, only the sharp edges so projecting contact with the surface of the material to be impressed, avoiding any pressure upon the material to be impressed other than that exerted by the sharp cutting edges of the die.

The characters of each die have sharp edges, so that they will make a cutting impression, and will not substantially displace the material of the web toward the opposite face. Each character extends beyond the peripheral surface of the roll a distance cor-

responding to the depth of the impression desired to be made upon the roofing.

In order to prevent the roofing from sticking to the die, means is provided for lubricating the face of the die-roll with a suitable lubricant, as for instance soap water or kerosene. In Figure 1 the under portion of the die-roll runs in a trough 8, which may contain the lubricant, there being a depth of lubricant in the trough just sufficient to submerge the die as it passes through the lubricant. The above arrangement is especially adapted for printing shingles, for shingles are cut with the weather side up and hence the impression of the trademark, label or the like must be on the underside of the web. In cutting roofing however, the arrangement shown in Figure 4 is preferable.

In this construction the die roller indicated at 9 is arranged above the web 10, and the platen roller 11 is arranged below the web. Both printing roll and platen roll are however, constructed in the manner shown in Figure 1. The printing or die roller is lubricated by means of a roller 12 journaled above the die roll, and having a facing 13 of felt or like absorbent material, which runs in contact with the peripheral surface of the die roll. This felt is soaked with a suitable lubricant, as for instance soap water or kerosene.

In both constructions the operation is the same. As the roofing is fed to the cutting rollers, and just before it is cut it is engaged by the die roll, which prints at regular intervals on the under surface of the web an impression of any desired character. Should the web be not of uniform thickness, yet the embossing will be alike throughout, since the platen roll and the printing roll may move toward and from each other in accordance with the varying thickness of the web.

In a machine of this character it is essential that the impressions be alike, regardless of the thickness of the web and regardless of its consistency. If the design is cut too deeply the web will tear, and if it is too shallow it may be obliterated by handling. In order to provide for a uniform impression regardless of thickness or consistency of the web, the die is mounted as above described, with only that part of the characters extending beyond the peripheral surface of the die which actually penetrate the web. Such characters must have sharp edges, in order that they will cut, and not offset the web, thus avoiding any marring or disturbing of the opposite surface of the material. The pressure exerted upon the sheet by the sharp cutting edges tends only to displace the material of the web laterally and not in the direction of the opposite face. In the arrangement illustrated,

the individual cutting edges act on the material somewhat as a wedge, making the impression by cutting the material and forcing it laterally. By providing a substantial portion of the cutting edges of the die below the surface of the printing member, a space is provided which tends to prevent the accumulation of sticky material upon the dies and the consequent gumming of the knife-edged parts of the die.

Obviously the apparatus for impressing the designs in the roofing need not be used in conjunction with the machine illustrated. Moreover, the invention is not limited to the specific details of construction herein shown, but may be variously modified. Although it is preferable to impress the material as one step of the process of manufacture, it is obvious that the invention may be embodied to impress the material at a subsequent stage, after the material has cooled, and either before or after the material is cut into units.

I claim:

1. Apparatus for impressing designs on webs of material of the kind described, comprising a printing or die member and a platen member between which the web is fed, the die member having depressions in its surface spaced to correspond with the spacing of the impressions desired, and dies in the depressions, the blank surfaces of the dies being within the surface of the die member and the impressing characters of the die extending beyond the surface thereof.

2. Apparatus for impressing designs on webs of material of the kind described, comprising a printing or die roll and a platen roll between which the web is fed, the die roll having depressions on its peripheral face spaced to correspond with the spacing of the impressions desired, and dies in the depressions, the blank surfaces of the dies being within the peripheral surface of the roll and the impressing characters of the die extending beyond the peripheral surface of the roll a distance corresponding to the depth of the impression desired.

3. Apparatus for impressing designs on webs of a soft and gummy nature, comprising a printing or die roll and a platen roll between which the web is fed, the die roll having depressions on its peripheral face spaced to correspond with the spacing of the impressions desired, and dies in the depressions, the blank surfaces of the dies being within the peripheral surface of the roll and the impressing characters of the die extending beyond the peripheral surface of the roll a distance corresponding to the depth of the impression desired, one of said rolls being mounted to yield away from the other and being spring pressed toward said other roll.

4. Apparatus for impressing designs on webs of material of the kind described, com-

prising a printing or die member and a platen member between which the web is fed, the die member having depressions in its surface spaced to correspond with the spacing of the impressions desired, and dies in the depressions, the blank surfaces of the dies being within the surface of the die member and the impressing characters of the die extending beyond the surface of the member, said members being yieldingly pressed toward each other.

5. Apparatus for impressing designs on webs of a soft and gummy nature, comprising a printing or die roll and a platen roll between which the web is fed, the die roll having depressions on its peripheral face spaced to correspond with the spacing of the impressions desired, dies in the depressions, the blank surfaces of the dies being within 10 the peripheral surface of the roll, said rolls being yieldingly pressed toward each other, and means controlled by the rotation of the die roll for lubricating said roll.

6. In a machine of the character specified, 15 a printing roll having dies depressed within the periphery of the roll, and having the printing characters of the dies extending beyond said peripheral surface.

7. In a machine of the character specified, 20 a printing roll having dies depressed within the periphery of the roll, and having the printing characters of the dies extending beyond said peripheral surface a distance corresponding to the depth of the impression desired.

8. Apparatus for impressing designs or identifying data on sheet material of the kind described, comprising in combination

a support for the sheet, a cutting device corresponding to the design to be impressed 40 having sharp edges whereby to cut the material of the sheet without substantially displacing it toward the opposite face of the sheet, and means for bringing said cutting device into contact with the sheet. 45

9. Apparatus for impressing designs or identifying data on sheet material of the kind described, comprising in combination a support for the sheet, a cutting device corresponding to the design to be impressed, having sharp edges whereby to cut the material of the sheet without substantially displacing it toward the opposite face of the sheet, means for moving said sheet across said support, and means for periodically bringing said cutting device into contact with the sheet. 50 55

10. Apparatus for impressing designs or identifying data on sheet material of the kind described, comprising in combination a support for the sheet, an impressing member carrying an impressing die having sharp edges which correspond with the design to be formed, the body of said die being carried below the surface of said member and the sharp edges thereof extending above the surface of said member for a portion only 60 of their height, means for moving said sheet across said support, and means for periodically bringing said impressing member into 65 contact with said sheet to form the design or data in said sheet by displacing the material of said sheet laterally and not toward the opposite side of the sheet. 70

In testimony whereof I affix my signature.
ALEXANDER S. SPEER.
